INFLATABLE TOY HORSE

Robert H. Wendt, Evanston, Ill.

Application June 1, 1951, Serial No. 15,381

Term of patent 14 years

(Cl. D34—15)

To all whom it may concern:

Be it known that I, Robert H. Wendt, a citizen of the United States, residing at Evanston, in the county of Cook and State of Illinois, have invented a new, original, and ornamental Design for Inflatable Toy Horse, of which the following is a specification, reference being had to the accompanying drawings, forming a part hereof.

Fig. 1 is a side elevational view of an inflatable toy horse showing my new design;

Fig. 2 is a top plan view;

Fig. 3 is a front elevational view.

This application is a continuation-in-part of my application, Serial No. D. 6,778, filed December 22, 1949.

I claim:

The ornamental design for an inflatable toy horse, as shown.

ROBERT H. WENDT.
